UNITED STATES PATENT OFFICE

MERLE NEWKIRK, OF MIDLAND, MICHIGAN

SECTIONAL GRATE

Application filed October 16, 1928. Serial No. 312,812.

This invention relates to stoker grates, and particularly to a sectional grate made up of a plurality of individual bars.

The prime object of the invention is to provide a nonsifting grate, which will prevent fine ash and fuel dropping into the air chamber, and thereby eliminate the possibility of burning out the extension grates, due to the ignition of an accumulation of siftings of fine ash and fuel therein.

Another object is to design a sectional grate so constructed that the air passages will not become clogged with ash and clinkers, thereby insuring an even and maximum volume of air being led to the fuel bed at all times.

A further object is to provide a grate having a smooth upper surface, so that clinker adhesion is reduced to a minimum, which is so ribbed as to dissipate heat, as well as rigidly reinforce the structure, and which is so shaped and mounted as to permit it to expand or "grow" without binding or warping.

The above and other objects will appear as the specification progresses, reference being had to the accompanying drawing in which I have shown the preferred embodiment of my invention, and in which like reference numerals indicate like parts throughout the several views thereof.

30 In the drawing,

Fig. 1 is a side view of one of the grate bars.

Fig. 2 is a top plan view showing several of the grate bars in assembled relation.

Fig. 3 is an end view of the grate bar shown 35 in Fig. 1.

Fig. 4 is a vertical sectional end view taken on the line 4—4 of Fig. 2.

Fig. 5 is a vertical sectional view taken on the line 5—5 of Fig. 1.

40 Fig. 6 is a fragmentary longitudinal sectional view taken on the line 6—6 of Fig. 1, the arrows indicate the direction of flow of the air.

Referring now particularly to the drawing, 45 the numeral 5 indicates the individual grate bars which are formed as clearly shown in Fig. 1 of the drawing, the upper surface being flat and smooth, the edge 6 overhanging the body of the structure, and is provided with spaced apart vertically disposed pas-

sages 7 therein, the opposite side being formed with spaced apart laterally projecting ribs 8, spaced from the top as shown, and having passages 9 therebetween, the back rib terminating in a shoulder 10 which is slightly 55 raised above the top of the ribs.

The back end of the bar is rounded over and projects downwardly at an angle, the lower end being notched as shown at 11, and is adapted to engage one leg of an obtuse angle 60 section 12 which forms the upper edge of the air chamber not shown, and I wish to direct particular attention to the fact that the front edge of the notch 11 is angled, so that as the grate bars expand or "grow" this back end of 65 the bar will rise accordingly, the angled edge riding up on the member 12, and compensating any expansion, a rib or fin 13 being cast integral with each bar structure, leading forwardly and terminating at a point spaced 70 from the front end of the bar.

The front end of the bar is angled as shown 75 at 14, the end resting on the stoker wall not shown, a lug 15 being cast on the bottom thereof, and a transversely disposed cored opening 16 is provided therethrough, and is adapted to receive a rod 17 for anchoring and rigidly securing the front ends of the bars together.

The bars when assembled are placed side 80 by side the back end of the lip 6 resting on the shoulder 10 as clearly shown in Figs. 2 and 6, the lip 6 overhanging the ribs 8, and being vertically spaced therefrom to provide a longitudinally disposed passage 18 there- 85 between, and I wish to direct particular attention to the fact that when the bars are in assembled relation, the passages 7 and 9 are not in vertical alinement, but are staggered, each passage opening into the longitudinally disposed passage 18.

The air chamber is of course located beneath the grate, and air flows through the passage 9 thence along the passage 18 and to the fuel through the passage 7, this forms 95 a tortuous passage, making it impossible for fine coal or ashes to sift through the grate bars and into the air chamber, this also insures a maximum volume of air without velocity, and the fins which are exposed 100

to the air chamber, effectively dissipate the heat as well as reinforcing the grate bars.

From the foregoing description it will be obvious that I have perfected a very efficient, substantial, and economical sectional grate for stokers.

What I claim is:

1. A sectional grate comprising a plurality of bars placed side by side, each bar being formed with an overhanging lip having a plurality of spaced apart passages therein, laterally projecting ribs on the opposite side of each bar and provided with passages therebetween, the passages between said ribs of the bar being in staggered relation to the passages in the lip of the adjacent bar.
2. A grate bar provided with a plurality of vertically disposed passages therein, a plurality of spaced apart laterally extending ribs on the opposite side of the bar, and a transversely disposed bearing on the back of the bar, the front wall of said bearing being angled.
3. A sectional grate comprising a plurality of bars placed side by side, spaced apart laterally projecting ribs on one side of each bar, a lip on the opposite side and overhanging the ribs on the adjacent bar to form a longitudinally disposed passage between said lip and ribs, and openings in said ribs and lips and communicating with said longitudinally disposed passage.
4. A sectional grate comprising a plurality of bars placed side by side, spaced apart laterally projecting ribs on one side of the bar, a lip on the opposite side adapted to overhang the ribs on the adjacent bar to form a longitudinally disposed air passage therebetween, vertically disposed passages between said ribs and in the overhanging lip, and communicating with the longitudinally disposed passages, the passages in the ribs being in staggered relation to the passages in the lip.
5. A grate bar formed with an overhanging lip having a plurality of passages therein, the front end of the bar being angled, the rear end being rounded over and extending downwardly and having a transversely disposed bearing formed therein, laterally projecting ribs on the opposite side of the bar and spaced from the top, passages between said ribs, and a fin formed on the bottom of said bar.

In testimony whereof I hereunto affix my signature.

MERLE NEWKIRK.
